(57) **CLAIM**

The ornamental design for a charging case for wireless earphones as shown and described.

DESCRIPTION

1. Charging case for wireless earphones

1.1 : Front

1.2 : Back

1.3 : Left

1.4 : Right

1.5 : Top

1.6 : Bottom

1.7 : Perspective

1.8 : Perspective

1.1 is a front view of a charging case for wireless earphones showing our new design; 1.2 is a rear view thereof; 1.3 is a left side view thereof; 1.4 is a right side view thereof; 1.5 is

(Continued)

a top view thereof; **1.6** is a bottom view thereof; **1.7** and **1.8** are perspective views thereof.

1 Claim, 8 Drawing Sheets
